INKSTAND

Frank M. Ashley, Great Kills, N. Y., assignor to
Lewis Gompers, trustee, New York, N. Y.

Application October 14, 1936, Serial No. 105,466

3 Claims. (Cl. 120—69)

My invention relates to inkstands.

The object of my invention is to provide an inkstand that may be filled with ink and shipped as a package.

5 A further object is to provide means whereby the inkstand may support a pen-holder which serves to close the tubular opening leading to the reservoir.

10 A further object is to provide a construction which may be made and marketed as a separate article of manufacture for use with bottles containing ink.

15 A further object is to provide a construction which will fit over and close the neck of a bottle such as is in general use for holding ink, and which will fit over bottles having necks of varying diameters.

20 A further object is to provide a construction which is made in a single piece, exclusive of the ink bottle or container, and the cover.

Referring to the drawing which forms a part of this specification:

25 Fig. 1 is a vertical sectional view in which the construction embodies a dip-tube for holding a pen-holder which serves to close the dip-tube opening.

Fig. 2 is a vertical sectional view thru a construction in which the cup is made from hard material such as hard rubber or plastic or fibre-board impregnated with material that is acid resisting to protect it from destruction, and the cup portion is made of soft vulcanized rubber, the top being formed to hold a cover in fluid-tight relation thereon.

35 10 indicates the bottle for holding ink and 11 the neck thereof.

12 indicates the usual beaded top formed on bottles for use with ink, and in Figure 2 is shown a bottle in which a thread is formed on the outer side of the neck for engagement with a cover.

40 Referring to the figures, the constructions shown therein each comprise a rubber cup 13 having a flexible flange portion 14 which is formed in the mould and in applying it to the top of the bottle, is stretched over the bead 12, the bead being large enough in diameter to cause the edges of the flange to turn inwardly and clasp the bead, as shown.

45 An upwardly extending flange portion of cylindrical form, 15 serves to form an upper chamber 16 over which a cover 17 fits in fluid-tight relation and is held thereon by forming the cover with depending inwardly inclined side walls 18 which underlie the wall of the chamber 16 as illustrated in Figure 1, for the same purpose, and in

which figure the cover side walls extend downward over the outer sides of the beaded portion 14 and protect the rubber from exposure while serving to provide a more ornamental package.

5 In Figures 1 and 2, a dip opening 18 is formed to support the lower end of a pen-holder which serves as a cork for the cup. In Figure 2, a separate ring portion 19 is used to clamp the cup in position on the bottle, the ring being preferably made of soft rubber, and the dip-opening is 10 formed in this ring.

The ring is provided with depending side flanges which are threaded to engage the threads formed on the outer side of the neck, as illustrated.

15 The top of the ring is provided with a vertically extending flange 20 provided with co-acting threads formed in the cover for holding the cover to the ring in air-tight relation.

The cup is filled by inverting the bottle, the ink filling the space above the openings 13 which 20 is of sufficient capacity to hold enough to fill the cup when the bottle is returned to its normal position of rest.

The construction is simple and efficient for the purpose designed.

25 Having thus described my invention I claim as new:

1. An inkstand comprising a bottle having an upstanding neck, a soft rubber insert for the neck including a cup closed at its lower end and 30 extending downwardly through said neck, an outer annular flange carried by the rubber insert between the upper and lower ends thereof for engagement with the outer side of the bottle neck for holding the rubber insert in position, said cup 35 having an opening in its side wall below and adjacent the outer annular flange whereby the tilting of the bottle fills the cup with ink, an inwardly directed annular flange on the soft rubber insert adapted to receive and support a pen 40 holder and to cooperate with the pen holder to provide a closure for the inkstand, an upstanding annular flange on the soft rubber insert surrounding the inwardly directed annular flange and a closure cap for the soft rubber insert and 45 bottle engaged with the upper edge of the upstanding annular flange and interlockingly engaged with the outer side thereof.

2. An inkstand comprising a bottle having an upstanding neck, a soft rubber insert for the 50 neck including a cup closed at its lower end and extending downwardly through said neck, an outer annular flange carried by the rubber insert between the upper and lower ends thereof for engagement with the outer side of the bottle 55

- neck for holding the rubber insert in position, said cup having an opening in its side wall below and adjacent the outer annular flange whereby the titling of the bottle fills the cup with ink, an inwardly directed annular flange on the soft rubber insert adapted to receive and support a pen holder and to cooperate with the pen holder to provide a closure for the inkstand, an upstanding annular flange on the soft rubber insert surrounding the inwardly directed annular flange and a closure cap for the soft rubber insert and bottle engaged with the upper edge of the upstanding annular flange and interlockingly engaged with the outer side thereof, said closure cap having a depending annular skirt surrounding the bottle neck engaging flange of the soft rubber insert.
3. An inkstand comprising a bottle having an upstanding neck, a soft rubber insert for the neck including a cup closed at its lower end and extending downwardly through said neck, an outer annular flange carried by the rubber insert between the upper and lower ends thereof for en-

gagement with the outer side of the bottle neck for holding the rubber insert in position, said cup having an opening in its side wall below and adjacent the outer annular flange whereby the titling of the bottle fills the cup with ink, an inwardly directed annular flange on the soft rubber insert adapted to receive and support a pen holder and to cooperate with the pen holder to provide a closure for the inkstand, an upstanding annular flange on the soft rubber insert surrounding the inwardly directed annular flange and a closure cap for the soft rubber insert and bottle engaged with the upper edge of the upstanding annular flange and interlockingly engaged with the outer side thereof, the cup of the soft rubber insert being separate from the flange elements and having a flange at its upper end resting in the bottle neck and clampingly engaged with the neck of the flange elements and the bottle neck-engaging flange having threaded engagement with the bottle neck.

FRANK M. ASHLEY.
